UNITED STATES PATENT OFFICE.

FRANK J. MACDONALD, OF AKRON, OHIO, ASSIGNOR TO THE B. F. GOODRICH COMPANY, OF NEW YORK, N. Y., A CORPORATION OF NEW YORK.

BOOT OR SHOE TREE.

Application filed June 28, 1921. Serial No. 480,957.

To all whom it may concern:

Be it known that I, FRANK J. MACDONALD, a citizen of the United States, residing at Akron, in the county of Summit and State 5 of Ohio, have invented a certain new and useful Boot or Shoe Tree, of which the following is a specification.

This invention relates to means for supporting a last in selective positions to facilitate the building or treatment of a boot 10 or shoe thereon, and is particularly applicable to the building up of rubber foot wear.

Its objects are to provide improved, simple means for the purpose stated, to provide a wide range of selective positions for the last and to provide means for preventing parts of the stock from wrinkling or sticking together before being placed in position in the boot or shoe, and for progressively applying stock to the last.

Of the accompanying drawings:

Fig. 1 is a side elevation of a preferred embodiment of my device.

Fig. 2 is an end elevation of the same with the last-supporting member in a different condition of adjustment.

Fig. 3 is a side elevation of the same showing another adjustment and with a last 30 in place and a shoe in process of construction thereon.

Fig. 4 is side elevation, showing another adjustment, with the work in place.

Referring to the drawings, 10 is a table 35 upon which are mounted a pair of brackets 11, 11, constituting a mounting for the parts hereinafter described. Between said brackets is pivoted an arm 12 adapted to be moved in a vertical plane from a substantially vertical position, as shown in Figs. 1, 2 and 4 to a substantially horizontal position, as shown in Fig. 3. Its hub is provided with friction washers 13, 13 adapted to be drawn against said hub by a thumb-nut 14 to brake 40 the movement of said arm. The latter is also formed with a toe 15 and an abutment face 16 adapted to abut the table 10 to limit the movement of said arm toward the vertical and horizontal positions respectively.

Upon the outer end of the arm 12 is pivoted, for relative movement of approximately 90° in the same vertical plane as said arm, a bracket or arm 17 formed with a bearing 17^a transverse to the pivotal axes of

said bracket and said arm. The hub of said bracket is provided with friction washers 18, 18 adapted to be drawn against said hub by a thumb-nut 19 to brake the movement of said bracket, said thumb-nut acting through 60 a clamping plate 20 held against rotation by dowel pins 21, 21 between said plate and said arm.

A face 22 of the bracket 17 is adapted to abut the arm 12 to limit the movement of 65 said bracket in one direction and said bracket is provided with a stud 23 adapted to abut the arm 12 to limit the bracket's movement in the opposite direction.

A plate 24 provided with a perpendicular 70 stem 25 is mounted in the bearing 17^a and 26 is a friction washer between the plate 24 and the bearing 17^a adapted to brake the turning of said plate. 27 is an anti-friction thrust-bearing interposed between the other end 75 of the bearing 17^a and the stem 25 to prevent the loosening of the nuts on said stem and to avoid any braking effect other than that of the friction washer 26. 28, 28 are posts mounted perpendicularly upon the 80 plate 24 and adapted to fit into holes in the base or leg of a last 29 to hold the latter in inverted position upon said plate.

The outer end of the plate 24 is formed with an open slot 24^a parallel with its face 85 in which are pivoted the inner ends of a pair of stock-anchoring fingers 30, 30 adapted for movement from and toward each other in the plane of said plate, the pivotal axes 30^a, 30^a of said fingers being substantially opposite the outline of the heel of the last. The outer ends of said fingers are bent upward toward the last and covered with rubberized fabric 30^b, 30^b, being thus adapted to receive and adhesively secure the ends of a 95 formed sheet of rubber shoe stock 31 partially applied to the last, to hold the same temporarily out of contact with each other and the last and to prevent them from becoming wrinkled or deformed while the rest 100 of the stock is being placed and rolled, and finally, if desired, to carry said ends successively around the heel of the last to apply the stock thereto progressively. 32, 32 are stop pins mounted upon the plate 24 and 105 adapted to be contacted by the fingers 30 to limit their movement away from each other.

The pins 32 are so positioned that when the fingers are stopped thereby the pull of the elastic stock 31 will be slightly off-cen- 110

ter, preventing said fingers from being swung toward each other by the pull of the stock. As the pivot 30 is substantially opposite or under the outline of the last, and 5 the said off-center effect is slight, the finger may be turned about its pivot to apply the stock progressively around the heel of the last without unduly changing the tension upon the stock. The stops 32 also prevent the fingers from departing unduly from 10 their operative positions.

With this apparatus the work may be given numerous working positions, with a sufficient frictional resistance against movement therefrom as to positions in which the lighter operations in building rubber 15 footwear are performed and positive resistance against the heavier forces applied in the building operation.

20 It will be observed that with the apparatus in the position shown in Fig. 1, for example, downward pressure upon the stock around the edge of the sole exerts a force which is resisted by the abutment of the 25 face 22 of the member 17 against the member 12, and as such force is substantially toward the pivotal axis of the member 12 it does not represent a substantial turning moment about said axis. In Fig. 4 there 30 is positive resistance against the force of the stock as it is stretched down over the last and attached to the fingers 30. As illustrating the many positioning possibilities of this device, it will be observed that the 35 last may be turned sole upward, about the axis of the bracket 17, at the low elevation represented by Fig. 3, or it may be turned sole upward at the higher elevation represented by Figs. 1, 2 and 4 and the last may 40 be turned through a complete revolution about the stem 25.

The details of construction may be varied without departing from the scope of my invention, and I do not wholly limit my claims 45 to the specific construction shown.

I claim:

1. A boot or shoe tree comprising a 50 mounting, a swinging arm hinged thereon and having a positively limited swinging range from a substantially horizontal to a substantially upright position, a second swinging arm hinged on the outer end of the first said arm, in outward extension thereof and on an axis substantially parallel with 55 the hinge axis of the first said arm, said second arm having a positively limited swinging range of approximately ninety degrees, and a last-supporting member adapted to hold a last in fixed relation thereto and pivotally mounted on said second arm 60 in outward extension thereof and on an axis transverse to that of the latter, and fixed with relation to said second arm.

2. A boot or shoe tree comprising a 65 mounting, a swinging arm hinged thereon

and having a positively limited swinging range from a substantially horizontal to a substantially upright position, a second, relatively short swinging arm hinged thereon on an axis substantially parallel with the hinge axis of said first arm, and a last-supporting member adapted to hold a last in fixed relation thereto and pivoted on said second arm, on an axis fixed with relation to said second arm, the second arm having a positively limited swinging range such that said last-supporting member and a last thereon may be swung over-center with relation to gravity and to the hinge of said second arm when said first arm is in either 75 its horizontal or its upright position.

3. A boot or shoe tree comprising a mounting, a series of swinging arms hinged to each other and the first hinged to said mounting, on parallel hinge axes, and a last support pivoted on the outermost one of 80 said arms on an axis transverse to said hinge axes, each of said arms having a positively limited swinging range about its hinge, said arms being so proportioned and 85 their swinging ranges being such that they may be turned to positions in which they will be positively stopped against a force applied to said last support toward said mounting, and to positions in which they will be positively stopped against a force 90 applied to said last support in a direction transverse to said axes and at right-angles to the combined length of said arms.

4. A boot or shoe tree comprising a 100 mounting, a swinging arm hinged thereon and having a positively limited swinging range from a substantially horizontal to a substantially upright position, a second arm hinged on the outer end of said first arm 105 on an axis parallel to the hinge axis of the latter, and a last support pivoted on said second arm, the swinging range of said second arm being such that when it is at one limit of said range a line drawn from 110 the pivotal center of a last mounted on said support to the hinge axis of the first arm will pass on one side of the hinge axis of the second arm, and when the second arm is at the other limit of its swinging range 115 such a line will pass on the other side of its hinge axis.

5. A boot or shoe tree comprising a mounting, a swinging arm hinged thereon and having a positively limited swinging 120 range from a substantially horizontal to a substantially upright position, a second swinging arm hinged on the outer end of the first arm on an axis parallel with the hinge axis of the latter, and a last support adapted 125 to hold a last in fixed relation thereto and pivoted on said second arm, on an axis fixed with relation to said second arm, the relation of said parts being such that with said first arm at either limit of its range a last 130

- mounted on said support may be revolved on the pivot of the latter with its sole substantially in either a vertical or a horizontal plane.
- 5 6. A boot or shoe tree comprising a last-supporting member and a stock-anchoring member pivoted thereon on a fixed axis transverse to the sole of the last, said stock-anchoring member being adapted to have 10 attached thereto a piece of stock partly applied to the work, and to be turned on its pivot, without movement of the latter, to apply said stock progressively to the last.
7. A boot or shoe tree comprising a last- 15 supporting member and a stock-anchoring member pivoted thereon on a fixed axis transverse to and adjacent the outline of
- the sole of the last, said member having a positively limited, pivotal range and being adapted, at the limit of its range, to hold 20 off-center a piece of stock partly applied to the last, and to be turned past-center from said position to apply said stock progressively to the last.
8. A boot or shoe tree comprising a last-supporting member and a pair of pivoted stock-anchoring members adapted to anchor the ends of the stock at a distance behind the heel portion of the last and separately 25 to be turned about said heel portion progressively to apply the stock thereto.

In witness whereof I have hereunto set my hand this 22 day of June, 1921.

FRANK J. MACDONALD.
